UNITED STATES PATENT OFFICE.

BERT R. WILLIAMSON, OF FAIRFIELD, MAINE, ASSIGNOR TO KEYES FIBRE COMPANY, OF FAIRFIELD, MAINE, A CORPORATION OF MAINE.

APPARATUS FOR MOLDING PULP ARTICLES.

1,360,847.

Specification of Letters Patent. Patented Nov. 30, 1920.

Application filed September 30, 1919. Serial No. 327,543.

To all whom it may concern:

Be it known that I, BERT R. WILLIAMSON, a citizen of the United States, residing at Fairfield, county of Somerset, State of 5 Maine, and whose post-office address is Fairfield, Maine, have invented an Improvement in Apparatus for Molding Pulp Articles, of which the following description, in connection with the accompanying drawing, is a 10 specification, like characters on the drawing representing like parts.

This invention relates to an apparatus for making articles such as pie plates and butter dishes from pulp. The general type of such 15 apparatus is disclosed in the patent to Chaplin No. 1,186,647 granted June 13, 1916, and the patent to Keyes No. 908,577 granted January 5, 1909 and comprises among other things a traveling mold, preferably a plurality of such molds, rotating about a central axis, the molds having a plurality of faces adapted to form the article between them, means to supply suitable pulp to the mold, and means to press the mold faces together 20 25 at a point farther on in the travel of the mold, whereby the pulp which has been delivered to the mold is pressed into an article of the desired shape.

The present invention relates particularly to means for stopping the traveling movement of the mold upon an improper action of the means to press the mold faces together.

In this type of apparatus the compression 30 of the mold faces at a given point in the travel of the mold is usually effected by passing the mold with its face closed upon the pulp between a pair of rigid jaws, one of which is provided with a movable compressor member or arm which acts to engage 35 the mold and travel with the mold, and compress it against the opposite jaw during the passage of the mold between the jaws. If this compressor member moves beyond a 40 point from which it will return to starting position it is liable to remain in such advanced position, and further operation of the apparatus will result in breakage of 45 some of the parts such as the stripping of 50 gears or the smashing of the mold members or their supports.

This invention has for its object to provide a simple and effective means for stopping the operation of the travel of the molds 55 or of the apparatus whenever this undesir-

able result occurs and thus protecting the apparatus against injury.

The drawings illustrate so much of an apparatus of the type disclosed in the patents above referred to as is necessary to a 60 disclosure of the present invention.

In the drawings—

Figure 1 is a front elevation of an apparatus such as shown in the patent to Chaplin above referred to.

Fig. 2 is a side elevation partially in cross section of that portion of the apparatus concerned with the present operation, the view being taken normally to the plan of the said device.

Fig. 3 is a view in cross section taken on the line 3—3 Fig. 2.

It will be understood that the particular form of apparatus illustrated is for the purpose of disclosing a preferred form of 75 the invention, but that the invention is not to be limited in its scope thereto, nor otherwise than as required by the claims.

The apparatus selected for disclosing the preferred form of the invention is so fully 80 set forth in the patents above referred to and prior patents that it is unnecessary to describe the apparatus in detail. It comprises a series of traveling molds each provided with two complemental separable 85 mold faces adapted to form therebetween a dish or hollow article such as a pie plate. These molds are shown as mounted on a rotary carrier, having a plurality of arms, one for each mold, and the circular path of 90 travel of the molds lies through a vat to which liquid pulp is supplied. The faces of the mold separate before entering the pulp vat, and the pulp is supplied by the aid of suction to the mold. Upon leaving the 95 vat the mold faces are brought together and then enter the compressing device, which operating with a tremendous pressure squeezes out mechanically a large amount of 100 water from the pulp and leaves the articles in such shape that upon the subsequent opening of the mold they may be removed therefrom by the aid of compressed air, and a suitable pick-off device.

The pulp vat is connected to cross bars 1 105 resting upon the floor 2 and extends beneath the floor. These cross bars support the shafts turning about the axis 3 which operate the traveling molds and the pick-off mechanism and through which the required vacuum and 110

compression is supplied. The molds are carried by a large spider like device comprising the ring member 4 provided at its periphery with the gear teeth 5. One member 6 of 5 each mold is fixed to the face of the ring member 4 while the other movable member 7 of each mold is carried by an arm 8 which permits it to swing to and from the fixed member while partaking of the rotary traveling 10 movement.

Brackets 9 and 10 extending vertically in front of and secured to the cross bar 1 support in suitable bearings a shaft 11. This shaft at one end is provided with a beveled 15 pinion 12 driving a beveled gear 13 to rotate a shaft 14 which in turn is geared to the gear teeth 5 of the ring member 4. At its opposite end the shaft 11 is provided with a beveled pinion 15 driving a beveled gear 20 16 for operating the pick-off mechanism. The shaft 11 may be driven in any suitable manner as by a belt 17 running on a pulley 18 fast to the shaft 11. A loose pulley 19 is also provided on the shaft 11 by the side 25 of the pulley 18 so that the machine may be stopped by shifting the belt 17 on to the loose pulley 19.

The compressing device is shown as of the type illustrated in the patent to Keyes No. 30 908,577 above referred to and comprises two jaws 20 and 21 which are preferably formed on a yoke shaped frame 22 preferably of iron or steel, hollow in form, and provided with a web 23 in the plane of the jaws so 35 that it is capable of resisting the large pressure of many tons which is necessary for the operation of expelling the water from the articles being molded. This compressing device for the reasons set forth in the said 40 patent to Keyes No. 908,577 is located so that its plane, or the plane in which the pressure takes place, is arranged radially to the mold carrier and at an angle to the horizontal equal to that which the mold must attain in 45 its travel in order to have the water drain out from the draining chamber of the mold by gravity. The mold carrier or ring member 4 travels through the compressing device with its face 24 riding against a plurality 50 of frusto conical rolls 25 arranged with their axes radial of the mold carrier and mounted in the jaw 20. The compression is effected by a compression member or arm 26 universally and pivotally mounted 55 in the jaw 21 and backed by heavy springs. This compression member at its free end is guided between suitable curved ways 27 and 28 supported from the yoke shaped frame 22. When in its lowermost position the 60 mold member 26 rests upon a buffer 29 at the bottom of the ways.

The operation of the compressing device is similar to that of a toggle. After the mold has received the pulp upon its face by 65 passing through the tank it travels up-

wardly between the jaws of the compressing device and as it enters these jaws it picks up the compression member so that as the mold continues its travel between the jaws the compression member gives a tremendous 70 pressure to the closed mold against the opposite jaw. As the mold passes out from between the jaws it leaves the compression member 26 which should thereupon drop back to its position on the buffer 29 ready to 75 act upon the next succeeding mold.

The compression member, however, may be carried to a position from which it will not return or fall back to its lowermost position on the buffer. When this happens it 80 will engage with the next succeeding mold or some moving part of the machine locking the mold carrier and causing the stripping of some of the gears or the smashing of the mold supports or otherwise injuring the ma- 85 chine.

This invention provides a simple and effective means for preventing these undesirable results and in the form shown provides means, which acts to shift the belt from the 90 fast to the loose pulley if and when the compressor member or arm passes beyond a predetermined point in its travel or beyond a point from which it will return to its lowermost position. A simple and preferred form 95 of means for securing this result is illustrated.

A rod 30 is mounted to slide in bearings in the brackets 9 and 10 and is provided with a fork 31 engaging the belt. At its opposite 100 end it is pivoted at 32 to a hand-operated lever 33 pivoted to a bracket 34 mounted upon the floor or carried by the cross bar 1. A spring 35 connected to the lever 33 and the cross bar 1 acts normally to shift the belt 105 from the fast pulley 18 to the loose pulley 19. The belt shipper 30 is held locked against the tension of the spring 35 with the belt on the fast pulley by means of a latch 36 recessed at its end to fit over an arm 37 110 extending upwardly from the belt shipper. This mechanism is so arranged that the latch 36 is raised from engagement with the arm 37 by the compressor arm if and when it passes beyond a predetermined point in its 115 travel or beyond a point from which it will return to starting position.

The latch 36 is secured to one end of a generally U shaped rocking member 38 pivoted in bearings 39 on the side of the yoke 120 shaped frame 22. This rocking member is supported with the latch 36 in engagement with the arm 37 by resting upon a projection 40 from the way 28. The end of the rocking member is prolonged to form a stop member 125 41 to catch the arm 37 upon release by the latch when the belt shipper has been moved sufficiently to bring the belt on to the loose pulley. At its opposite end the rocking member 38 extends adjacent the ways 28 and 130

27 and has adjustably secured thereto by the bolts 42 a feeler 43 projecting in the path of travel of the arm 26. This feeler is so mounted and adjusted that if the arm 26 at 5 the conclusion of its travel in compressing the mold passes beyond a point necessary for that purpose, or beyond a predetermined point, or beyond a point from which it will return to its lowermost position it will, contacting with the feeler 43, rock the rocking member 38, thus releasing the latch 36 and causing the belt to be moved from the fast pulley 18 to the loose pulley 19 under the action of the spring 35 thus stopping the 15 operation of the machine.

The compressor arm may then be returned by hand to its lowermost position and the machine re-started by throwing the hand lever 33 in the opposite direction against the 20 tension of the spring 35 to bring the belt back to the fast pulley and the arm 37 into engagement with the latch 36, the upper end of the arm 37 being beveled or curved as indicated at 44 to cam the latch into place.

25 Having thus described my invention what I claim as new and desire to secure by Letters Patent is—

1. An apparatus for molding pulp articles comprising a traveling mold formed of 30 a plurality of separable mold faces, means for effecting the travel of the mold, a pair of jaws mounted transversely of the path of travel of the mold to allow the mold to pass between them, a compressor arm mounted in 35 one of said jaws and acting to engage the mold and travel with the mold and compress the mold against the opposite jaw during the passage of the mold between the jaws, and means acting to stop the traveling 40 movement of the mold upon the passage of the compressor arm beyond a predetermined point in its travel.

2. An apparatus for molding pulp articles comprising a traveling mold formed of 45 a plurality of separable mold faces, means for effecting the travel of the mold, a pair of jaws mounted transversely of the path of travel of the mold to allow the mold to pass between them, a compressor arm 50 mounted in one of said jaws and acting to engage the mold and travel with the mold and compress the mold against the opposite jaw during the passage of the mold between the jaws, and means actuated by the 55 compressor arm upon its movement beyond a predetermined point in its travel to stop the traveling movement of the mold.

3. An apparatus for molding pulp articles comprising a traveling mold formed of 60 a plurality of separable mold faces, means for effecting the travel of the mold, a pair of jaws mounted transversely of the path of travel of the mold to allow the mold to pass between them, a compressor arm 65 mounted in one of said jaws and acting to

engage the mold and travel with the mold and compress the mold against the opposite jaw during the passage of the mold between the jaws, means for stopping the travel of the molds, and a latch for restraining the 70 operation of said stopping means positioned to be released by the compressor arm if and when it passes in its travel beyond a predetermined point.

4. An apparatus for molding pulp articles comprising a traveling mold formed of a plurality of separable mold faces, driving means including a belt and a fast and a loose pulley for effecting the travel of the mold, a pair of jaws mounted transversely 75 of the path of travel of the mold to allow the mold to pass between them, a compressor arm mounted in one of said jaws and acting to engage the mold and travel with the mold and compress the mold against the 80 opposite jaw during the passage of the mold between the jaws, a belt shipper, means acting to move the belt shipper to shift the belt from the fast to the loose pulley, means for locking the belt shipper 85 in position to maintain the belt upon the fast pulley, and means for unlocking the belt shipper if and when the compressor arm passes in its travel beyond a predetermined point.

5. An apparatus for molding pulp articles comprising a traveling mold formed of a plurality of separable mold faces, driving means including a belt and a fast and a loose pulley for effecting the travel of the 100 mold, a pair of jaws mounted transversely of the path of travel of the mold to allow the mold to pass between them, a compressor arm mounted in one of said jaws and acting to engage the mold and travel with the mold 105 and compress the mold against the opposite jaw during the passage of the mold between the jaws, a belt shipper, means acting to move the belt shipper to shift the belt from the fast to the loose pulley, means for locking the belt shipper in position to maintain the belt upon the fast pulley, and means for 110 unlocking the belt shipper actuated by the compressor arm if and when it passes in its travel beyond a predetermined point.

6. An apparatus for molding pulp articles comprising a traveling mold formed of a plurality of separable mold faces, means for effecting the travel of the mold, means acting to engage the mold and travel with 120 the mold and compress the mold during a given period in the travel of the mold, and means acting to stop the traveling movement of the mold actuated by the compressing means if and when it moves beyond a 125 predetermined point in its travel.

7. An apparatus for molding pulp articles comprising a rotatable ring member, a plurality of molds, each composed of separable mold faces supported by and traveling 130

with said ring member, means for rotating the ring member, a yoke shaped frame mounted transversely of the path of travel of the ring member to allow the molds to 5 pass between its jaws, a compressor arm mounted in one of said jaws and acting to engage each mold and travel with the mold and compress the mold against the opposite jaw during the passage of the molds 10 between the jaws, means for stopping the rotation of the ring member, a latch pivotally mounted upon the yoke shaped frame having one portion extending into the path of travel of the compressor arm and another 15 portion normally acting to restrain the means for stopping the travel of the molds,

whereby upon the passage of the compressor arm beyond a predetermined point in its travel the latch will be rocked to release the stopping mechanism and effect the stopping 20 of the rotation of the ring member.

8. An apparatus for molding pulp comprising the construction defined in claim 7 in which the said latch is provided with an adjustable feeler extending in the path of 25 travel of the compressor arm whereby the point at which the latch releases the stopping mechanism may be adjusted.

In testimony whereof I have signed my name to this specification.

BERT R. WILLIAMSON
